Specification for Design.

Patented May 5, 1914.

Application filed February 19, 1914. Serial No. 819,848. Term of patent 14 years.

To all whom it may concern:

Be it known that I, CHARLES E. DANIELS, a citizen of the United States, and a resident of Sandusky, county of Erie, and State of Ohio, have invented a new, original, and ornamental Design for Cartons, of which the following is a specification, reference being had to the accompanying drawing, forming part thereof.

In said annexed drawing:—the single figure there appearing is a perspective view of a carton showing my new and ornamental design.

I claim:—

The ornamental design for a carton, as shown.

Signed by me this 17th day of Feb., 1914.

CHARLES E. DANIELS.
